UNITED STATES PATENT OFFICE.

CLIFTON W. SHERMAN, OF BUFFALO, NEW YORK.

DRAFT-RIGGING.

1,314,369.

Specification of Letters Patent. Patented Aug. 26, 1919.

Application filed August 21, 1914. Serial No. 857,859.

To all whom it may concern:

Be it known that I, CLIFTON W. SHERMAN, a citizen of the United States, residing at Buffalo, in the county of Erie and State of New York, have invented new and useful Improvements in Draft-Rigging, of which the following is a specification.

This invention relates to a draft rigging for railway cars and more particularly to devices of this character in which the cushioning effect for taking up the blow or strain during buffing or pulling of the car is taken up by springs.

One of the objects of this invention is to provide a follower for a draft rigging of this character which is so constructed that it better resists the strains which tend to bend the same and which is provided with means preferably formed integrally therewith which serve to limit the extent of travel of the follower so as to distribute the strain more uniformly throughout the draft rigging, retain the cushioning springs in their proper place and also limit the tension under which the springs may be placed during buffing or pulling.

Another object of this invention is to so construct the followers that the bearing area of the same is increased and to so construct the yoke that it assists to a greater extent in taking part of the buffing strains or shocks in connection with the cheek plates on the sills of the car.

A further object of this invention is to provide means for using this draft rigging either with a coupler having a slotted shank or a coupler in which the shank is unslotted and avoiding the use of any rivets for holding the coupler in position.

A still further object of this invention is to increase the effective bearing area on the cheek plates, in the most approved organization of this draft rigging, without slotting the sills of the car.

This invention has the further object to improve the draft rigging in various details of construction as will appear more clearly farther on.

In the accompanying drawings:

Figure 1 is a horizontal longitudinal section of a draft rigging associated with the shank of a car coupler and the draft sills of a car and embodying my improvements. Fig. 2 is a vertical longitudinal section taken

centrally through the same. Figs. 3 and 4 are vertical transverse sections taken in the correspondingly numbered lines in Fig. 2. Fig. 5 is a detached elevation of one of the cheek plates. Fig. 6 is a fragmentary vertical longitudinal section taken in line 6—6, 60 Fig. 7 and showing the means for connecting the shank of the car coupler with the yoke straps when this shank is not provided with a key slot. Fig. 7 is a fragmentary horizontal section taken in line 7—7, Fig. 6. 65 Fig. 8 is a detached perspective view of one of the coupling or retaining bars or keys which are employed for connecting the yoke straps with a car coupler having an unslotted shank. Fig. 9 is a fragmentary perspective view of the connecting bar whereby the rear end of the cheek plates are connected and the rear ends of the yoke straps are 70 slidingly supported.

Similar characters of reference indicate 75 corresponding parts throughout the several views.

1, 1 represents the two longitudinal draft sills of the bar body which are preferably constructed of channel irons having their 80 flanges turned outwardly in the usual well known manner. The upper ends or edges of these draft sills may be connected by a tie plate 2, as shown in Figs. 2, 3 and 4, for the purpose of holding them rigidly in their 85 proper spaced relation although this may be accomplished in any other suitable manner, if desired.

3 represents the shank of a car coupler 90 which is arranged with its rear end between the front parts of the car sills and provided on its upper and lower sides with forwardly-facing shoulders 4, 5 for use in connecting the same with the yoke-straps 6, 6 of the draft rigging without passing a key through 95 the shank and which is also provided in its rear part with a slot or opening 7 extending horizontally and transversely through the same, so as to permit of connecting the coupler shank with the yoke-straps by passing 100 a key 8 through the slot 7, if this should be preferred by some car builders or railroad officials.

In the space between the sills in rear of the coupler shank are arranged front and 105 rear followers 9, 10, the front follower normally engaging its front side with the rear end of the coupler shank while the rear fol-

lower is arranged in rear of the front follower and is separated therefrom by an intervening space. The front follower is provided on its horizontally opposite sides with laterally projecting guiding and supporting arms 11 and on its rear side with a rearwardly projecting stop or spacing block 12, said arms and spacing block being arranged midway between the upper and lower ends 10 of the front followers. The rear follower is provided on its horizontally opposite sides with laterally projecting guiding and supporting arms 13 and on its front side with a forwardly projecting spacing or stop block 14, the guiding arms and stop block of the rear follower being also arranged midway between the upper and lower ends of this follower. Each of the followers is preferably formed integrally with its companion stop block and guide arms and these elements are preferably constructed of cast steel and suitably cored or hollowed out so as to render the same very strong and durable and not liable to bend under any strains 25 to which they are subjected and still not employ an undue amount of metal in the construction of the same.

15, 16 represent the inner and outer sections of an upper spring which is interposed between the opposing upper parts of the followers and 17, 18 the inner and outer sections of a lower spring which is arranged between the lower parts of the opposing sides of the front and rear followers. The 30 opposing parts of the outer sections of the upper and lower springs engage with concave seats 19 formed on the upper and lower sides of the stop blocks, so as to conform to the curvature of these spring sections, and the opposite ends of the coils of the 35 inner spring sections surround centering or retaining bosses, ferrules or lugs 20 which are formed on the opposing sides of the followers, and thereby serve to confine the 40 springs between the followers and prevent lateral as well as vertical displacement thereof. These bosses are preferably made hollow, as shown at 21 in Figs. 2, 3, and 4, so as to permit of passing tie bolts through 45 the openings of these bosses and centrally through the two sets of springs, as shown by dotted lines 22 in Fig. 2, and drawing the two followers together by engaging the 50 heads and nuts of the bolts with the outer sides of the followers for the purpose of 55 temporarily connecting the followers and placing the springs under an initial strain while assembling the parts of the draft rigging. After the draft rigging is assembled, 60 the bolts 22 connecting the followers are removed from the bosses thereof.

The two yoke-straps 6, 6 are preferably constructed of cast steel and arranged lengthwise on opposite sides of the coupler 65 shank and the followers and springs and

each strap is provided in its front part with a longitudinal slot 23 adapted to receive the respective end of the coupler key 8, if one is used, while the rear end of this yoke strap is provided with a longitudinal slot 70 24 through which the guiding and supporting arms on the respective side of the followers are adapted to project laterally. In the normal or relaxed condition of the draft rigging the coupler key 8 engages its front 75 edge with the front ends of these front slots in the yoke-straps while its rear edge is separated by an intervening space from the rear ends of these slots, and at this time the front sides of the guide arms of the front follower engage with the front ends of the rear slots of the yoke-straps and the rear sides of the arms of the rear follower engage with the rear ends of the rear slots in the yoke-straps, as shown in Fig. 1. 80

The upper and lower parts of the followers are somewhat narrower than the diameter of the large sections of the springs, so that the latter project horizontally or laterally beyond the lateral edges of the followers above and below the guiding or supporting arms thereof, as shown in Fig. 3. 85

The yoke-straps are arranged close to the horizontally opposite sides of the upper and lower springs and the upper and lower ends 90 of the followers. The inner sides of the yoke-straps are provided with inwardly-projecting swells or enlargements 25 which taper inwardly, each swell on one strap extending inwardly beyond a vertical line 100 drawn from the periphery of one of the outer spring sections to the other, so that these swells are arranged in the spaces between the marginal parts of these springs and the latter overlap the swell of each 105 yoke-strap. By this means the available space between the upper and lower springs is utilized for accommodating an increase in the cross sectional area of the yoke-straps, whereby the latter are able to resist a much 110 greater strain while the draft rigging is subjected to a pulling or buffing action. At its rear end each of the yoke-straps is provided with an inwardly projecting and a forwardly-facing abutment 26 the face of 115 which is transversely in line with the rear end of the companion rear slot in the yoke-strap and engages with the rear side of the rear follower, so as to increase the bearing area of the strap against the rear follower 120 and more effectually resist the buffing and pulling strains to which the same is subjected.

The inner sides of the webs of the draft 125 sills are provided with cheek plates which are preferably constructed of cast steel and serve, in the most approved construction of my invention, as the sole support for the draft rigging without necessitating the formation of any slots in the sills so that they 130

are more efficient in resisting the strains to which they are subjected, although these cheek plates may be slotted to some extent in order to meet some conditions and still 5 retain other advantageous features of my invention. Each of these cheek plates comprises an upright body 27 which is secured at suitable points throughout the length thereof to the inner side of the companion 10 sill by means of rivets 28 and is provided at its front end with a rearwardly facing front abutment 29 which is adapted to engage with the front end of the companion yoke-strap, and at its rear end with a forwardly- 15 facing rear abutment 30 which is adapted to engage with the rear end of the companion yoke-strap. In the normal or relaxed condition of the draft rigging the yoke-straps engage their rear ends with the 20 rear abutments of the cheek plates, while the front ends of the yoke straps are separated from the front abutment of the cheek plates by intervening spaces, as shown in Fig. 1. Between its front and rear abutments each of the cheek plates is provided 25 with a front slot 31, a longitudinal intermediate slot 32 and a longitudinal rear slot 33. The front slot 31 is not usually employed in the most approved form of my draft rigging 30 but is merely provided in each of the cheek plates for use in connecting a coupler having a slotted shank for the reception of a key 8 which also passes through the yoke-straps, cheek plates and draft sills, if this should be 35 desired by railroad officials or car builders having a preference for this construction. When the front slots 31 are employed in the cheek plates, the adjacent parts of the sills are also provided with coinciding longitudi- 40 nal slots 34 for the reception of the key 8 which connects the shank of the coupler with the yoke-straps and slidably supports the same on the cheek plates and car sills, but if the connection between the coupler and 45 the yoke straps is effected without the use of a key 8 passing through a slot in the coupler shank, then the front slots 31 in the cheek plates and the companion slots in the car sills may be omitted, thereby avoiding weak- 50 ening of the latter. The intermediate slot 32 of each cheek plate opens downwardly by a mouth or passage 35 extending from the lower side of this slot to the lower edge of the respective cheek plate, which mouth or 55 passage has its walls preferably converging upwardly and opening into the lower part of the intermediate slot, so as to leave comparatively short bottom portions or shoulders 36, 37 of this slot at opposite ends thereof. The rear slot 33 of each cheek plate is similarly provided with a mouth or passage 38 extending from the lower side of this slot to the lower edge of this cheek plate, the walls of this mouth converging upwardly 60 and preferably into the central part of the

respective rear slot so as to form short bottom portions or shoulders 39, 40 on the lower side of the rear slot at opposite ends thereof, as shown in Fig. 5. The arms on opposite sides of the front follower are arranged with their extremities within the central or intermediate slots of the cheek plates and in the normal or relaxed condition of the draft rigging engage their front sides with the front ends of the intermediate slots, 70 and resting on the front shoulders 36, as shown in Fig. 1. The arms of the front follower are introduced into the intermediate slot or removed therefrom by passing the same vertically through the passages leading to the lower sides of the intermediate slots. The arms of the rear follower are arranged with their extremities in the rear slots 33 of the cheek plates and in the normal or relaxed position of the draft rigging bear 80 with their rear sides against the rear ends of the rear slots in the cheek plates, and also rest on the rear shoulders 40 thereof, as indicated in Fig. 1. These arms of the rear follower are introduced into the rear slots 90 or removed therefrom by moving the same vertically through the passages communicating with the lower side of the rear slots in the cheek plates. Both followers with the springs slightly compressed between 95 them while temporarily coupled or assembled by means of bolts 22 passing through the hollow bosses 20 may be simultaneously moved so that their arms enter the intermediate and rear slots of the cheek plates by 100 moving the guide arms of the followers upwardly into the intermediate and rear slots, and these parts may be in like manner simultaneously removed from the intermediate and rear slots of the cheek plates when it 105 is desired to dismember the draft rigging. While the follower arms are thus coupled with or uncoupled from the cheek plates the yoke straps are mounted on said arms. After the arms of the follower have been placed 110 within the intermediate and rear slots of the cheek plate, the temporary tie bolts 22 are removed so as to permit the springs to expand and press the arms of the front follower normally against the front ends of 115 the intermediate slots and the arms of the rear follower are normally engaged with the rear ends of the rear slots of the cheek plates.

In the normal or relaxed condition of the parts of the draft rigging, the stop blocks 120 of the two followers are separated from each other, and the key 8 is arranged in its central position within the front slots 31 of the cheek plates and the slots 34 of the sills, so that the front and rear edges of this key 125 are separated by intervening spaces from the front and rear ends of the slots 31, 34, as shown in Fig. 1.

When the car coupler is subjected to a buffing action during which the same moves 130

rearwardly or inwardly relatively to the car sills, the yoke straps are held at rest by engagement of their rear ends with the rear abutments of the cheek plates and the rear follower is also held at rest by engagement of the same and its guide arm with the rear ends of the rear slots of the cheek plates and yoke straps and the abutments on the latter, while the front follower moves rearwardly 5 together with the coupler shank and the coupler key 8. This rearward movement of the front follower, coupler shank and key 8 relatively to the sills, cheek plates, straps and rear follower continue until the stop 10 block of the front follower engages with the stop block of the rear follower, the guide arms of the front follower engage with the rear ends of the intermediate slots in the cheek plates and the coupler key 8 engages 15 its rear edge with the rear ends of the front slots in the yoke straps and the rear ends of the slots 31, 34 in the cheek plates and sills. This simultaneous engagement of the coupler key with the rear ends of the slots 23, 20 25 31, 34 by the engagement of the front follower arms with the rear ends of the slots 32 and the engagement of the front block with the rear stop-block is secured by so constructing the parts that in the normal or relaxed 30 35 position of the draft rigging the distances between the stop blocks, between the arms of the front follower and the rear ends of the slots 31, and between the rear edge of the key 8 and the rear ends of the slots 31, 34 is alike. By this means the first part of the shock during the buffing action of the coupler is taken up or cushioned by the springs until the stop blocks engage with each other, the front guide arms 40 45 bear against the rear ends of the slots 32 of the cheek plates and the coupler key 8 bears against the rear ends of the slots 34, 31 and 23 of the sills, cheek plates and yoke-straps after which the buffing thrust is transmitted 50 55 directly from the coupler to the sills through the medium of the intermediate connecting parts. In the rearmost position of the front follower its arms rest on the rear shoulders 37 of the intermediate slots 32. It will be noted that during the final or last part of the buffing action the strains are transmitted from the coupler to the sills partly by the key 8, cheek plates and yoke straps, partly by the front follower and cheek plates, 60 65 partly by the front and rear followers and cheek plates and partly by the front and rear followers, yoke straps and cheek plates, whereby these buffing strains are distributed among the several members of the draft rigging and over practically the entire length of the cheek plates which are attached to the sills, thereby materially increasing the strength of the draft rigging and enabling the same to withstand a much 65 greater buffing strain with safety.

During a pulling action of the coupler, the front follower remains at rest by reason of its guide arms engaging with the front ends of the intermediate slots in the cheek plates, while the yoke-straps are moved forwardly by the key 8 which connects the same with the coupler and the rear follower is moved forwardly by the yoke-straps. During the initial portion of this pulling action of the coupler, the springs between the 70 75 followers are compressed until the stop block of the rear follower engages with the corresponding block of the front follower, this engagement between these stop blocks occurring at the same time that the front sides of 80 the rear follower guide arms engage with the front ends of the rear cheek plate slots 33 also at the same time that the front edge of the coupler key 8 engages with the front end of the slots 31, 34 in the cheek plates and 85 sills and also at the same time that the front ends of the yoke straps engage with the front abutments of the cheek plates, this effect being obtained by so constructing the parts that in the normal or relaxed position 90 of the draft rigging the distances between the front ends of the yoke straps and the front abutments, between the front of the coupler key 8 and the front ends of the slots 31, 34, and between the front sides of the 95 rear follower guide arms and the front ends of the rear slots 33 are the same as the normal distance between the stop blocks of the followers. As the result of this construction of the parts referred to, the last 100 portion of the pulling strains of the coupler are transmitted partly to the sills by direct engagement therewith of the coupler key 8, also partly by engagement of this key with the front ends of the slots 31 105 in the cheek plates, also partly by the coupler key 8, yoke-straps, front cheek plate abutments, partly by engagement of the front follower arms with the front ends of the intermediate slots 32 of the cheek plates 110 and partly by engagement of the rear follower arms with the front ends of the rear slots 33 in the cheek plates, thereby distributing these pulling strains among the several elements of the draft rigging and practically equalizing the strain over the entire length of the cheek plates, so as to enable them to bear a greater load with safety. In the foremost position of the rear follower its arms rest on the front shoulders 39 of the 115 rear slots of the cheek plates. By thus distributing the strain during buffing and pulling actions of the coupler among the different elements of the draft rigging, undue wear or elongation at opposite ends of the 120 slots in the yoke-straps, cheek plates and sills is avoided and this permits of maintaining the draft rigging in its best working condition for a greater length of time before necessitating adjustment or repairs to cor- 125 130

rect an undesirable, abnormal condition. Inasmuch as the followers are always under tension or strain as they move lengthwise their arms do not tend to drop through the 5 passages 35, 38 as they pass over the same during buffing and pulling.

For the purpose of enabling the strains of the buffing and pulling actions of the coupler to be distributed with practical uniformity over the several rivets which connect the cheek plates at different points throughout their length with the sills, each of these cheek plates has the front, intermediate and rear slots thereof bounded by 10 means of inwardly projecting ribs or flanges 41 and the flanges of these several slots are connected with each other and with the front and rear abutments by means of longitudinal tension webs or plates 42, 43, 44, 45 which 15 are offset inwardly from the main part or body of the cheek plates, as shown in Figs. 1 and 5. By means of these ribs or flanges and tension plates or webs, the strains to which the cheek plates are subjected are not 20 transmitted successively from the rivets in one part of each cheek plate to those in another part of the same, but instead are carried directly to the several rivets of each cheek plate, so that they all operate simultaneously 25 to resist the shock or strain to which this plate is subjected, thereby increasing the strength and durability of the draft rigging. Inasmuch as the buffing strains are usually heavier than the pulling 30 strains, additional means are provided for stiffening and strengthening the rear parts of the cheek plates and sustaining the rear abutments of the same against the shock to which they are subjected, and for this purpose 35 each of the cheek plates is provided on its upper edge with a longitudinal stiffening or strengthening rib or flange 46 which extends from the central part of this plate to the upper end of the rear abutment and gradually 40 becomes wider from its front end toward its rear end, as shown by full lines in Fig. 5 and by dotted lines in Fig. 1. By this means the cheek plates are materially stiffened so as to strengthen the same where 45 most needed when subjected to shock.

It will be noted that the solid parts of the cheek plates between the intermediate and rear slots thereof form in effect intermediate stops to limit the rearward movement of the 50 front follower during the buffing action of the car coupler and to limit the forward movement of the rear follower during the pulling action of the coupler, which double function of this part of the cheek plates 55 materially simplifies the construction of the draft rigging.

Means are provided for causing the followers while in a normal or resting position to become interlocked with the plates so that 60 either one or the other of the followers when

at rest and receiving the thrust of either a buffing or pulling action will operate to aid in holding the cheek plates and connected parts in their normal position and prevent the same from spreading. This is preferably 70 accomplished by providing the front sides of the guide arms of the front follower with offset or tapering portions or enlargements 47, the front sides of which are preferably inclined so that the arms of the front 75 follower flare or enlarge laterally outward and the front ends 48 of the intermediate slots of the cheek plates are correspondingly undercut so as to present inclined bearing faces which are adapted to be engaged by 80 the inclined faces of the front follower guide arms, as shown in Fig. 1. By this means, a hook-like engagement of the front follower with the cheek plates is effected in the foremost position of this follower which 85 causes the latter to serve as a tie or connecting member between the cheek plates and hold the latter against spreading while under strain. Similar lateral enlargements or tapering portions 49 are formed on the rear 90 sides of the rear guide arms of the rear follower, these enlargements or offsets having inclined faces which engage with correspondingly inclined faces 50 formed by undercutting the rear ends of the rear slots 95 in the cheek plates, whereby the rear follower while in its rearmost position forms a tie or connecting member between the rear parts of the cheek plates and prevents these portions from spreading while subjected to 100 buffing strains.

Additional means are provided for connecting the rear ends of the cheek plates so as to hold the same against spreading which means also are preferably so constructed 105 that they aid the followers and the coupler key in supporting the various movable parts of the draft rigging. In the preferred form of this rear connection between the cheek plates the same comprises a transverse tie 110 bar or plate 51 which is provided at its opposite ends with T-shaped enlargements or heads 52 each of which is adapted to engage with an undercut longitudinal seat, groove or slot 53 preferably of T-shape form in 115 cross section arranged on the rear end of one of the cheek plates and closed at its front end by a shoulder 54 while its rear end is open. The respective head 52 of the tie bar 51 is confined in the undercut groove 53 120 by means of a retaining or locking pin 55 passing vertically through corresponding openings in the adjacent part of the cheek plate and past the rear edge of the tie bar, so as to confine the latter in said undercut 125 groove or seat. This tie bar can be readily applied to the cheek plates while assembling the parts of the draft gear and can also be readily removed therefrom when it is desired to dismember the draft rigging. Each 130

of the locking pins 55 is preferably held in place by bending the ends thereof, as shown in Fig. 2, so as to prevent accidental withdrawal thereof from the respective cheek 5 plate.

The rear end of each yoke strap is provided with a longitudinal slot 56 which receives the adjacent front part of the rear tie bar. In the normal or relaxed condition of 10 the parts the yoke-straps are supported upon the rear tie bar 51 to such an extent that when the yoke-straps are drawn forwardly during the pulling action of the coupler to their fullest extent parts of the yoke-strap 15 will still remain in engagement with this rear tie bar, thereby serving as a guide and a support for the rear ends of the yoke straps at all times and aiding in supporting the straps, the followers and associated 20 parts, so as to relieve the follower-arms and the slots of the cheek plates from undue wear.

When the coupler which is available is provided with a shank having no slot for 25 the reception of the key 8, means are provided whereby the same may be connected with the yoke straps without the necessity of any riveting or similar operation for this purpose, which means also are preferably 30 so constructed that they serve as ties or connecting members between the front ends of the yoke-straps above and below the shank of the coupler. The preferred means for coupling the shank and the yoke-straps is 35 shown in Figs. 1, 2, 4, 6, 7 and 8 and are constructed as follows:

57, 57 represent upper and lower inlet grooves formed lengthwise on the inner side of each yoke-strap at a point above and below 40 the coupler shank. Each of these inlet grooves opens forwardly at the front end of the respective yoke-strap while its rear end is undercut and preferably beveled, as shown at 58. On the longitudinal side of 45 each inlet groove next to the coupler shank the same is provided with a vertically-extending enlargement forming a seat 59 the ends of which are preferably undercut so that each of these seats is of substantially 50 dove-tail form in a lateral direction. 60, 60 represent two coupling keys or bars which are preferably constructed in the form of plates and arranged crosswise above and below the coupler shank and in position to engage 55 their rear edges with the shoulders 4, 5 of the car coupled. At its opposite ends each of these coupling bars is provided with 60 enlargements 61, preferably of dove tail form, which are adapted to engage with the dove tail seats 59 on the adjacent parts of 65 the yoke-straps. These coupling bars are engaged with these seats and the coupler shank by first sliding the ends of these coupling bars rearwardly through the inlet 70 groove 57 of the yoke straps and then mov-

ing the same vertically so that they engage the upper and lower sides of the car coupler and their dove tail ends engage the companion seats 59 of the yoke-straps and the rear edges of the coupling bars engage with the respective shoulders 4, 5 of the car coupler. The coupling bars are then held in this position by similar retaining or locking bars or plates 62 each of which also is provided at its opposite ends with dove tail enlargements 62. Each of these retaining bars is moved with its ends rearwardly in the inlet grooves 57 until the same is vertically in alignment with the companion coupling bar 60 and engages with the outer side of the same and the dove tail end of the respective locking bar 61 engages with the dove-tail rear end of the respective inlet groove. Each of the retaining or locking bars is confined in its proper position 80 within its inlet grooves by means of retaining or locking pins 63 inserted through openings in the front parts of the yoke-straps so as to stand in front of each retaining bar after which this retaining pin is 90 bent laterally at its inner end, as shown in Fig. 2, for the purpose of preventing the same from becoming detached. When both pairs of coupling and retaining bars have been thus assembled in connection with the 95 yoke straps and the shank of the car coupler, the latter is reliably held in place on the yoke straps and capable of withstanding the severest pulling strains to which the draft rigging is liable to be subjected.

The parts heretofore described of themselves constitute sufficient means for guiding and supporting the movable parts of the draft rigging, but if desired, additional means may be provided for supporting and 100 guiding these parts, such for instance, as the pan-shaped hanger 64 engaging with the lower parts of the followers and the outer sections of the lower spring and secured at its opposite ends to the lower edges of the 105 side sills, and a cross bar 65 connected with the lower edges of the sills and engaging with the lower edges of the front parts of the yoke-straps, as shown in Figs. 2, 3 and 4.

In this improved draft rigging the car 110 coupler can be taken out and replaced by another without requiring the removal of the follower springs and associated parts, and it is also possible to remove the followers, 115 springs and associated parts, without removing the car coupler.

By casting the spacing or stop blocks integrally with the followers the strength of the followers is materially increased so that they are not liable to buckle or bend when 120 under maximum strains. These stop blocks furthermore limit the extent which the followers may approach each other so that undue straining of the springs is prevented and a core or housing is formed for the springs 125 130

which prevents distortion as well as climbing of the springs which otherwise would be liable to occur.

I claim as my invention:

5. 1. A draft rigging, comprising two cheek plates provided with longitudinal slots having downwardly-opening passages which are shorter than the slots so as to form upwardly facing seats at the ends of said slots, and a follower arranged between said plates and having laterally projecting arms which are adapted to pass vertically through said passages and to move horizontally in said slots. 70
15. 2. A draft rigging, comprising two cheek plates each of which is provided with a forwardly-facing rear abutment and a longitudinal flange which increases in width from its front end toward said rear abutment, and 75 a follower movably mounted on said cheek plates and adapted to engage said abutments. 20
3. A draft rigging, comprising cheek plates each provided with longitudinal guide slots, abutments, holes arranged at different 80 points in the length of the plate and adapted to receive bolts for securing the plate to a sill, ribs arranged around said slots and connecting with said abutments, and laterally offset webs connecting said ribs with each 85 other and with said abutments, and supporting members guided in said slots and adapted to engage with said abutments. 90
4. A draft rigging, comprising cheek plates each of which is provided at its front 95 end with a rearwardly facing abutment and at its rear end with a forwardly facing abutment, yoke straps adapted to engage lengthwise at their front and rear ends with said front and rear abutments, and followers mounted on said straps. 100
5. A draft rigging, comprising cheek plates each of which is provided at its front end with a rearwardly facing abutment and at its rear end with a forwardly-facing abutment, yoke straps adapted to engage lengthwise at the front and rear ends with said front and rear abutments, and followers mounted on said straps and guided on said cheek plates. 110
50. 6. A draft rigging, comprising two followers, upper and lower coil springs interposed between the upper and lower parts of said followers, yoke-straps arranged lengthwise on opposite sides of the springs and 115 each provided on its inner side with a longitudinal swell which projects inwardly between the adjacent opposing outer parts of the upper and lower springs and cheek plates on which said followers are guided. 120
60. 7. A draft rigging, comprising two cheek plates each of which is provided with an abutment and with guide-slots, yoke-straps adapted to engage at their rear ends with said abutments and provided with guide 125 slots, followers provided with arms engaging with the slots of said cheek plates and yoke-straps, and provided with stop blocks on their opposing sides which limit the movement of said followers toward each other, springs interposed between said followers, 70 said followers upon reaching the limit of their longitudinal movement in either direction being adapted to bear against each other and against said cheek plates, and at the same time said yoke straps are adapted to 75 bear against said abutments and one of said followers is adapted to bear against said abutments and a coupler connected with said straps and engaging with the front follower. 80
8. A draft rigging, comprising two cheek plates each provided with a rear abutment and two guide slots, two yoke-straps each adapted to engage its rear end with the rear abutment of one of said cheek plates and having a longitudinal slot, front and rear 85 followers movable toward and from each other and having arms and stop blocks on their opposing sides, the arms of the rear follower projecting through said slots of the yoke-straps and the rearward pair of slots 90 in said cheek plates, and the arms of the front follower projecting through said slots of the yoke-straps and the forward pair of slots of said cheek plates, springs interposed between said followers. 95
9. A draft rigging, comprising two cheek plates each provided with a rear abutment and two guide slots, two yoke-straps each adapted to engage its rear end with the rear abutment of one of said cheek plates and 100 having a longitudinal slot, front and rear followers movable toward and from each other and having arms and stop blocks on their opposing sides, the arms of the rear follower projecting through said slots of the 105 yoke-straps and the rearward pair of slots in said cheek plates, and the arms of the front follower projecting through said slots of the yoke-straps and the forward pair of slots of said cheek plates, springs interposed 110 between said followers, said parts being constructed to cause the engagement of the rear ends of the yoke-straps with said rear abutments, the engagement of the rear follower with the rear ends of the slots in the yoke-straps and the rear ends of the rearward slots in the cheek plates, the engagement of the stop blocks of the followers, and the engagement of the front follower with the rear ends of the forward slots in the cheek plates 115 to be affected simultaneously, and a coupler connected with said straps and engaging with the front follower. 120
10. A draft rigging, comprising two cheek plates each provided with a front abutment 125 and two guide slots, two yoke-straps each adapted to engage its front end with said front abutment and having a longitudinal slot, front and rear followers movable toward and from each other and having arms, 130

and stop blocks on the opposing sides of the followers, the arms of the rear follower projecting through said slots of the yoke-straps and the rearward pair of slots in said cheek 5 plates and the arms of the front follower projecting through the slots of the yoke-straps and the forward pair of slots in said cheek plates, springs interposed between said followers, and a coupler connected with said 10 straps and engaging with the front follower.

11. A draft rigging, comprising two cheek plates each provided with a front abutment and two guide slots, two yoke-straps each adapted to engage its front end with 15 said front abutment and having a longitudinal slot, front and rear followers movable toward and from each other and having arms, and stop block on the opposing sides of the followers, the arms of the rear 20 follower projecting through said slots of the yoke straps and the rearward pair of slots in said cheek plates and the arms of the front follower projecting through the slots of the yoke-straps and the forward 25 pair of slots in said cheek plates, springs interposed between said followers, said parts being constructed to cause the engagement of the front ends of the yoke straps with said front abutments, the engagement of 30 the rear follower with the front ends of said rearward slots in the cheek plates, the engagement of the front follower with the front ends of the forward slots in the cheek plates, the engagement of the 35 stop blocks of the followers, and the engagement of the rear ends of the slots in the yoke-straps with the rear follower to be effected simultaneously, and a coupler connected with said straps and engaging with 40 the front follower.

12. A draft rigging, comprising two cheek plates each provided with front, intermediate and rear slots and front, and rear abutments, yoke-straps normally engaging their 45 rear ends with said rear abutments and each provided with front and rear slots, a rear follower normally engaging its rear side with the rear ends of the rear slots in the cheek plates and yoke-straps, and provided 50 on its front side with a stop block, a rear follower normally engaging its front side with the front ends of the rear slots in the yoke-straps and the intermediate slots in said cheek plates, springs interposed be- 55 tween the followers, a coupler arranged between the yoke straps and bearing against the front side of the front follower, a key extending through said coupler and normally engaging its front edge with the front 60 ends of the front slots in said yoke-straps and normally arranged in the front slots of the cheek plates midway between the front and rear ends thereof and a coupler connected with said straps and engaging with the 65 front follower.

13. A draft rigging, comprising two cheek plates each provided with front, intermediate and rear slots and front and rear abutments and passage-ways leading to said intermediate and rear slots, yoke-straps normally engaging their rear ends with said rear abutments and each provided with front and rear slots, a rear follower having arms movable through the passage-ways of the rear cheek plate slots and normally engaging their rear sides with the rear ends of the rear slots in the cheek plates and yoke-straps, and provided on its front side with a stop block, a front follower having arms movable through the passage-ways of the intermediate cheek plate slots and normally engaging their front sides with the front ends of the rear slots in the yoke-straps and the intermediate slots in said cheek plates, springs interposed between the 80 followers, a coupler arranged between the yoke-straps and bearing against the front side of the front follower, and a key extending through said coupler and normally engaging its front edge with the front ends of the front slots in said yoke-straps and normally arranged in the front slots of the cheek plates midway between the front and rear ends thereof, the distance normally between the stop blocks, between the front side of the rear follower and the front ends of the rear slots in the cheek plates, between the rear side of the front follower and the rear ends of the intermediate slots in the cheek plates, between the rear edge of the 90 coupler key and the rear edges of the front slots in the yoke-straps, and between the front and rear edges of the coupler key and the front and rear ends of the front slots in the cheek plates being the same. 95

14. A draft rigging, comprising two cheek plates each of which is provided at its rear end with a longitudinal undercut slot which is provided at its front end with a shoulder, a transverse tie bar provided at its opposite 110 ends with heads engaging with said slots, and retaining pins arranged on said cheek plates at the rear ends of said plates.

15. A draft rigging, comprising two cheek plates, a transverse tie bar mounted at its 115 opposite ends on said cheek plates, yoke-straps guided at their rear ends on said tie bar, and followers mounted on said yoke-straps.

16. A draft rigging, comprising two cheek 120 plates, a transverse tie bar mounted at its opposite ends on said cheek plates, yoke-straps each provided at its rear end with a longitudinal slot which receives said tie bar, and followers mounted on said yoke-straps. 125

17. A draft rigging, comprising two yoke-straps each of which is provided on the inner side of its front end with a longitudinal groove having a beveled inner end and a dovetail socket arranged on one side of said 130

groove and opening vertically into the same at the inner end thereof, a main transverse coupling bar provided with dovetail ends engaging with the dove-tail sockets of said 5 yoke-straps, a coupler having a shank provided with a forwardly-facing shoulder engaging with the rear edge of said coupling bar, an auxiliary transverse retaining bar engaging with said coupling bar and having 10 dovetail ends engaging with the beveled inner ends of the longitudinal grooves in said yoke-straps, retaining pins mounted on the yoke-straps and projecting across the front parts of said grooves in said yoke-straps, 15 cheek plates, followers mounted on said straps and plates, and springs interposed between said followers.

18. A draft rigging, comprising two cheek plates provided with guide-ways and pas-

sages leading to said guide-ways, two followers arranged between said cheek plates and having arms arranged in said guide-ways and adapted to be moved through said passages, upper and lower springs arranged one above the other and between said followers, said followers being narrower than the diameter of said springs, and yoke-straps arranged between opposite sides of said springs and followers and the cheek plates and each strap having its inner side 30 projecting into the space between the adjacent parts of the upper and lower springs.

Witness my hand this 20th day of August, 1914.

CLIFTON W. SHERMAN.
